C. F. T. Steinway.

Sheet 1-2 Sheets.

Piano-Forte.

No. 97,982.

Patented Dec. 14, 1869.

A detailed technical drawing of a mechanical assembly, labeled 'Fig. 2' in the lower-left corner. The drawing shows a central vertical rod with a flared top and a flared base. At the top, there is a rectangular frame with a hinged door. The central rod has several horizontal slots and a central vertical slot. At the bottom, there is a base plate with a central slot and a small circular component. The drawing uses hatching and cross-hatching to indicate different parts and materials.

C. F. TH. STEINWAY, OF NEW YORK, N. Y.

Letters Patent No. 97,982, dated December 14, 1869.

IMPROVEMENT IN PIANO-FORTES.

The Schedule referred to in these Letters Patent and making part of the same:

To all whom it may concern:

Be it known that I, C. F. TH. STEINWAY, of the city, county, and State of New York, have invented a new and useful Improvement in Piano-Fortes; and I do hereby declare the following to be a full, clear, and exact description thereof, which will enable those skilled in the art to make and use the same, reference being had to the accompanying drawing, forming part of this specification, in which drawing—

Figure 1 represents a plan or top view of this invention.

Figure 2. is a longitudinal vertical section of the same, the line $x x$, fig. 1, indicating the plane of section.

Figure 3 is a horizontal section of the same.

Figure 4 is a transverse section of the same, taken in the plane indicated by the line $y y$, fig. 1.

Figure 5 is a plan or top view of the sounding-board detached.

Similar letters indicate corresponding parts:

This invention relates principally to certain improvements on a patent for an improvement in piano-forte, granted to my brother, William Steinway, June 5, 1866, and numbered 55,385, which improvement was particularly designed for upright piano-fortes, while the principal object of my present improvements is to render the invention described in the above-named patent applicable to grand piano-fortes.

This improvement consists in extending the sounding-board bridge in an unbroken curve from the treble-end to the bass-end of an overstrung piano-forte, in such a manner that the vibrations of each string are transmitted to the whole sounding-board, and thereby the fulness and evenness of the tone are materially improved; further, in the arrangement of a raised portion on the metal frame, in such a manner that room is obtained for the sounding-board bridge, which extends in an unbroken curve from the treble-end of the piano-forte to the bass-end; also, in the arrangement of a top treble-bar passing, at the wrest-plank end of the metal frame, over a series of treble-strings, and at the bass-end between a number of bass-strings, in such a manner that the strain and leverage exerted by the strings hitched to the top of said bar, are counteracted by the strain of the strings passing through under it, and the quality of the instrument to retain its tune is materially improved; further, in the arrangement of a semi-cylindrical edge at the closed parts of the metal frame, in such a manner that in the connection of the top and bottom part of said metal frames, the greatest possible strength is preserved, and thereby, and by avoiding sharp corners in the metal frame, the tone of the instrument is improved; also, in the arrangement of connecting-bearers or braces, extending from the bottom plate of the metal frame under the tuning-block extension of the top plate of

said metal frame, and provided with shoulders to support that edge of the sounding-board which extends across the keys, in such a manner that room for the action of the mechanism, and also a firm support for the tuning-block and sounding-board, are obtained, without breaking the connection between the top and bottom plates of the metal frame; further, in the arrangement of blocks, which rise from the bottom of the wooden case of a piano-forte, through openings in the bottom plate of the metal frame, and form the supports for the sounding-board, in combination with corresponding openings in the top plate of the metal frame, in such a manner that easy access can be had to the screws which serve to fasten the sounding-board down upon the blocks, and thereby the operation of securing the sounding-board in position is materially facilitated; also, in exposing the bottom of the wooden case of a piano-forte, together with the sounding-board, to a compressing-force produced by screws, wedges, wire-draws, or other suitable means, in such a manner, that by the action of the said bottom, combined with that of the sounding-board, the volume of the tone is materially increased; further, in the arrangement of standards or blocks, which rise from the bottom of the wooden case, and form the supports for the metal frame, in such a manner that a firm connection between the metal frame and the wooden case can be effected, and at the same time the bottom of said case is prevented from coming in direct contact with the metal frame, and its vibrating power is preserved intact; also, in the arrangement of the braces, which extend from the semi-cylindrical edge of the metal frame to that wall of the wooden case which is situated under the open side of the metal frame, so that by said braces the compressing-force in this direction is counteracted; further, in the arrangement of a flap or lid, which is hinged to the bottom edge of the front piece of the wooden case, and which, when turned up, forms the support or desk of the music, the hinges being so placed that they remain concealed when said flap is closed as well as when it is open; also, in the peculiar arrangement of the cheek-pieces of the action-frame, said cheek-pieces being made to catch in front over the key-rail, and in the rear over the shoulders of the standards supporting the front pieces of the case, in such a manner that by removing said cheek-pieces, the action of the frame and the front part of the case are released, and the operation of taking the piano-forte apart or putting it together, is materially facilitated.

In the drawings—

The letter A designates a wooden case for a grand piano-forte, constructed in the usual manner, and supported by legs B.

From the bottom C of this case, near its curved

edge, rises a series of detached blocks, *a*, which, together with the two strips *b c*, form the supports for the metal frame *D*.

This metal frame is constructed on the principle described in the above-mentioned Letters Patent, No. 55,383, being composed of a top plate, *d*, and a bottom plate, *e*, which are united by a rim, *f*, leaving an open space for the reception of the sounding-board *E*.

The rim *f* of my plate, however, unlike that shown in the above-mentioned Letters Patent, is semi-cylindrical, best seen in figs. 2 and 4, so that in the connection of the top and bottom plates, the greatest possible strength and firmness are obtained, and that all sharp corners are avoided, whereby the clearness of the tone of my instrument is materially improved.

The sounding-board *E* is provided with a single bridge, *F*, which extends in an unbroken curve from the treble-end to the bass-end, as shown in figs. 1 and 5.

By this arrangement of the sounding-board bridge, the vibrations of each string are transmitted directly to the entire sounding-board, and the tone of the instrument remains uniform throughout.

In order to make room for the bight of the bridge *F*, the top plate of the metal frame is provided with a raised part, *g*, which extends over the bridge, and to the outer edge of which is hitched a series of strings, *s*, which extend through under the raised part *g*, instead of over the frame-plate, as shown in figs. 1 and 2 of the drawings.

From the treble-end of the metal frame *D* extends a top bar or rib, *h*, to the bass-end of said plate.

A series of treble-strings, *s*, extends through under said top bar, while a series of bass-strings, *s'*, is hitched to its upper surface.

This last-mentioned series of bass-strings exerts a leverage which has a tendency to twist the outer part of the top plate *d* downward, and this strain is counteracted by the strings *s* and *s'*, which have a tendency to twist said outer part of the top plate in the opposite direction.

By the position of the top bar *h*, in relation to the strings *s s'*, the metal frame is enabled to sustain the strain of the several strings, and the quality of the instrument to retain its tone is materially improved.

The metal frame *D* is bolted down to the blocks *a* and strips *b c*, which retain it at an elevation above the bottom of the case *A*, so as to prevent the metal frame from coming in direct contact with the bottom, and by placing the blocks *a* at certain distances apart, the vibrating quality of said bottom is preserved.

From the bottom *C* rises a series of wooden blocks or standards *i*, through apertures *j* in the bottom plate of the metal frame, and to these standards the sounding-board is firmly secured by screw-bolts *k*, the upper plate of the metal frame being also provided with apertures *l l*, corresponding to the apertures *j* in the bottom plate, so that easy access can be had to the screw-bolts *k*, for the purpose of fastening or unfastening the sounding-board.

By means of the screw-bolts *k* and standards *i*, the sounding-board is firmly connected to the bottom *C* of the case, and both the sounding-board and bottom *C*, together, are exposed to the compressing-force of set-screws *m*, which are tapped in the semi-cylindrical edge of the metal frame, and bear on the standard *i*.

By this arrangement, the vibrating power of the sounding-board and the bottom *C* is materially increased, the transverse vibrations of the edges of the sounding-board are prevented, and thereby the volume of the tone of the instrument is improved.

It is obvious, that in place of the set-screws, other devices, such as wedges or wire-draws, might be substituted, to exert the required compression on the bottom *C* and sounding-board *E*.

From the semi-cylindrical edge of the metal frame *D*, extend braces *n*, which hook over the long, straight side of the case *A*, or over that side which is under the open part of the metal frame, so that by said braces the force of the set-screws is counteracted, and the opposite side of the case is prevented from being forced out.

The top plate *d* of the metal frame extends at one end beyond the bottom plate, and to this extension is secured the tuning-block *H*. (See fig. 2.)

Suitable braces *o*, which rise from the bottom plate *e*, serve to support and stiffen the tuning-block extension of the top plate, and between these braces sufficient room is left for the introduction of the action.

The inner edges of said braces form shoulders or abutments, against which the block or strip *p* bears, which serves to support the front edge of the sounding-board.

By this arrangement a firm connection of the top and bottom plates at the front end of the metal frame is effected, without interfering with the action-mechanism, and at the same time a firm and substantial support for the front end of the sounding-board is obtained.

The key-board of the piano-forte is covered by a flap or lid, *I*, which is hinged to the lower edge of the front piece *J* of the case *A*, the hinges being so applied, that they are perfectly concealed, whereby the appearance of the instrument is materially improved.

To the inner surface of the flap *I* is secured a strip, *q*, so that when said flap is turned up, it serves as a support for the music, and a music-desk is thus obtained, which is superior to the ordinary music-desk on grand piano-fortes, because it brings the music in such a position that the performer is enabled to take in, at one glance of the eyes, the music as well as the keys, while, with the ordinary arrangement of the desk, the music is placed at such an elevation above the key-board, that the performer is compelled to turn his eyes constantly from the keys to the music, and vice versa.

The front piece *J* of the case *A*, and the key-rail *K*, are both retained in position by the cheek-pieces *L* of the action-frame, said cheek-pieces being made to overlap the key-rail, and also a shoulder, *r*, on the standards *t*, which support the front piece *J*, so that by removing the cheek-pieces, the front piece *J* and the action-frame are both released, and the operation of taking the instrument apart and putting it together is materially facilitated.

The upper surfaces of the cheek-pieces *L* are flush with those of the side-strips *M* of the case, so that on each side of the key-board a spacious platform is formed for the support of lamps or other articles.

Having thus described my invention, I want to be distinctly understood that I disclaim everything shown and described in the patent of my brother, William Steinway, dated June 5, 1866; but

What I claim as new, and desire to secure by Letters Patent, is—

1. Extending the sounding-board bridge of an over-strung piano-forte, in an unbroken curve, from the treble to the bass-end, substantially as and for the purpose described.

2. In combination with the continuous sounding-board bridge, the arrangement of a raised part on the top plate of the metal frame, the strings running under the plate instead of over, substantially as set forth.

3. The treble-bar *h* of the metal frame *D*, arranged, in relation to the strings *s s'*, substantially in the manner shown and described.

4. The semi-cylindrical edge or rim *f* of the metal frame *D*, as set forth.
5. The braces *o*, forming the connection between the bottom plate *c* of the metal frame and the tuning-block extension of the top plate *d*, and forming shoulders or abutments for the front edge of the sounding-board, substantially as described.
6. The arrangement of blocks or standards *i*, rising from the bottom of the case *A*, through apertures in the bottom plate of the metal frame, and forming the connection between said bottom and sounding-board, substantially as set forth.
7. Subjecting the bottom of the case *A*, together with the sounding-board, to a compressing-force produced by screws, wedges, or other suitable devices, substantially as shown and described.
8. The detached blocks *a*, rising from the bottom of the case *A*, and forming the supports of the metal frame *D*, substantially as set forth.
9. The metal bands or braces *n*, extending from the rim *f* of the metal frame to that side of the case *A* which is situated under the open end of the metal frame, said braces serving to counteract the compressing-force of the screws or other devices bearing on the sounding-board and bottom *C* of the case, as set forth.

C. F. TH. STEINWAY.
